CLAIM

The ornamental design for a convertible sofa with ottoman, as shown and described.

DESCRIPTION

FIG. 1 is a front, right side perspective view of a convertible sofa with ottoman showing my new design;

FIG. 2 is a front view thereof showing only the convertible sofa;

FIG. 3 is a front, right side perspective view thereof;

FIG. 4 is a front, right side perspective view thereof in a second position;

FIG. 5 is a front, right side perspective view thereof in a third position;

FIG. 6 is a front, right side perspective view thereof in a fourth position;

FIG. 7 is a right side view of the convertible sofa of FIG. 3;

FIG. 8 is a left side view thereof;

FIG. 9 is a rear, right side perspective view thereof;

FIG. 10 is a bottom, left side perspective view of the convertible sofa of FIG. 5;

FIG. 11 is a front, right side perspective view showing only the ottoman;

FIG. 12 is a front, right side perspective view thereof in a second position; and,

FIG. 13 is a front, right side perspective view thereof in a third position.

The convertible sofa and the ottoman are shown separated in some figures to show aspects of the design that are not visible when combined.

The broken lines showing a power cord in FIG. 9 and a zipper in FIG. 10 show portions of the convertible sofa with ottoman, which form no part of the claimed design.
